METHOD AND APPARATUS FOR ROLLING
UNIFORM GAUGE STOCK

Arthur J. Townsend and Edward S. Miller, Canton, Ohio, assignors, by mesne assignments, to Harry M. Naugle and Arthur J. Townsend, both of Canton, Ohio

Application November 18, 1932, Serial No. 643,188

16 Claims. (Cl. 80—35)

The invention relates to the hot or cold rolling of metal strips, stripsheets and the like, and more particularly to a method of and apparatus for continuously rolling steel strips, stripsheets and the like to uniform gauge.

The usual hot roughing and finishing rolling of hot rolled strips has been accomplished by utilizing a reversing rough rolling mill in which the rough rolling of a slab is performed by passing a slab alternately back and forth through the reversing mill; after which the rough rolled slab is finish rolled in several stands of mills arranged in tandem to make hot rolled strips.

The output of a reversing rough rolling mill is somewhat restricted but the operation of the same is quite flexible; and due to the fact that alternate ends of the slab being rolled enter the mill alternately, the roughing operation delivers a piece which is accurate to gauge from end to end.

Quite recently, in order to substantially increase the output of roughing and finishing hot mills, continuous roughing and finishing mills, comprising in certain cases some nine stands of hot mills arranged in tandem, have been used to make hot rolled strips or stripsheets from slabs. In such continuous roughing mills, the first four or five stands have been termed the "roughing" or "break-down" stands and the succeeding five or four stands have been termed the "finishing" stands.

The forward end of the material being rolled enters each stand of the continuous train first, in carrying out a continuous hot roughing and finishing operation to make strips or stripsheets, so that the rear end of the material being rolled is delivered to the finishing stands, and particularly to the last finishing stand, at a substantially greater gauge than the front end of the material.

This variation in gauge from end to end of the material being rolled occurs because the rear end of the material has cooled to a lower temperature, as it reaches each stand of the continuous train of rolls, than the forward end of the material being rolled as the forward end reaches each roll stand.

If a variation in gauge of a hot rolled strip or stripsheet which may be from 300 to 800 feet, more or less, in length, is once established, it is difficult, if not impossible to eliminate the gauge variation in subsequent rolling operations.

As a result of this condition of variation in gauge of strips or stripsheets hot rolled in a continuous roughing and finishing mill, it has been found necessary to reduce the finished length of

the material being rolled so that variations in gauge from end to end of the strip or stripsheet may be maintained within commercially required limits.

The reduction of the finished length of hot rolled strips or stripsheets materially handicaps the subsequent performance of continuous pickling and cold rolling of the material, so that in many cases it has been necessary to weld short pieces of hot rolled strips or stripsheets together for subsequently performing continuous pickling or cold rolling operations, in order to secure a length of material which will permit greater economy in carrying out such operations.

It has been proposed to automatically compensate for gauge variations of material delivered from a mill by gauging the material as it is delivered from the mill with a gauging device, which is electrically connected with the screw down motors, to open or close the gap between the rolls as gauge variations occur in the material delivered. While it may be possible, to a limited degree, to gauge with a gauging device material delivered on the delivery side of a slowly operating cold mill, it is impractical if not impossible to accurately gauge hot material as it is delivered from the delivery side of a continuous hot mill, particularly at the delivery side of the last mill stand, where the speed of the material may be from 500 to 1000 feet per minute.

Accordingly, it is an object of the present invention to provide a method of and apparatus for automatically compensating for or eliminating gauge variations existing from end to end in material being rolled in a continuous rolling mill.

It is a further object of the present invention to anticipate the variation in gauge, which cumulatively occurs from end to end of strips or stripsheets being rolled in a continuous rolling mill, and to correct in a cumulative manner the gauge variation, to produce uniform gauge material.

Moreover it is an object of the present invention to automatically adjust the rolls of a rolling mill, by interconnected mechanical and electrical means, preferably synchronized with or operated by the main mill drive motor, to compensate for gauge variations which may exist from end to end in the material being rolled, while the material is passing through the mill.

The variation in gauge which may occur from end to end of a piece being rolled in a hot mill because the rear end of the piece is cooler than the forward end thereof, results in the piece being

progressively thicker from its forward end to its rear end.

It is therefore a further object of the present invention to compensate for such a gauge variation in continuous hot rolling by lowering the upper roll at predetermined intervals a predetermined amount in coordination with the revolutions made by the rolls, and by adjusting the amount that the upper roll is lowered and/or the intervals of lowering, in accordance with the total gauge correction to be made to produce uniform gauge material.

It is likewise an object of the present invention to provide for the adjustment of the mill screws by automatic and interconnected mechanical and electrical devices to lower the mill screws a desired amount progressively at intervals to decrease the gap between the rolls for compensating for heavier gauges progressively existing from the forward end to the rear end of the material being rolled.

It is also an object of the present invention to roll uniform gauge material in a rolling mill by controlling the operation of the mill screw down motor by and in synchronism with operation of the mill drive means, or the rolls driven thereby, or with the movement of the material through the rolls, to compensate for variations in the gauge of material being rolled by the mill while the material is passing therethrough.

In certain cases, in carrying out a cold rolling of strip or strip sheet material, gauge variation may occur in the finished material, and it is comprehended within the scope of the present invention to automatically compensate for or eliminate gauge variations existing from end to end in material being rolled in a continuous mill whether the operation is a hot rolling operation or a cold rolling operation, although hot rolling operations are described in detail herein.

Moreover, it is an object of the present invention to provide a means for automatically compensating for or eliminating gauge variations existing from end to end in material being rolled in a rolling mill, and to provide means for adjusting the compensating means to enable the handling of materials of different delivered lengths and of materials having different rates of gauge variations.

And finally, it is an object of the present invention to avoid the difficulties of gauge variation experienced in prior rolling practice by providing a method of and apparatus for compensating for gauge variations existing from end to end in material being rolled in a rolling mill, which methods and apparatus may be readily utilized in connection with standard existing equipment.

These and other objects may be obtained by the methods and apparatus, a preferred embodiment of which is shown in the drawings and herein-after described in detail and claimed, which may be stated in general terms as including in a rolling mill having a screw down motor and a drive motor, means for operating the screw down motor automatically to adjust the gap between the mill rolls a predetermined amount at predetermined intervals as the material being rolled passes through the rolls, said means being operated preferably by the entry of material to the rolls, said means being preferably operated by the exit of the material from the rolls to re-establish the original roll gap setting, and there being means provided for adjusting the interval of and/or amount of roll adjustment.

In the drawings,

Figure 1 is an elevation view of the entering side of a rolling mill stand equipped with the present improvements;

Fig. 2 is an enlarged side elevation section of the roll stand shown in Fig. 1, taken on the line 2-2, Fig. 1; and

Fig. 3 is a wiring diagram, including diagrammatic illustrations of a mechanical switch operating means, of the interconnected mechanical and electrical means utilized in carrying out the present invention.

Similar numerals refer to similar parts throughout the drawings.

A four high roll stand is generally indicated in Figs. 1 and 2 at 4, which may preferably be the last roll stand of a tandem arranged continuous rolling mill and may include the usual mill frame members 5 having mounted therein a lower back up roll 6, a lower work roll 7, and upper work roll 8 and an upper back up roll 9. The lower back up roll 6 and lower work roll 7 are mounted in the usual relatively fixed bearings 10 and 11, respectively, while the upper work roll 8 and the upper back up roll 9 are mounted in the usual adjustable bearings 12 and 13, respectively.

The upper back up roll 9 may preferably be adjusted vertically at each end by the usual roll adjusting screws 14 operated by screw down motors 17a and 17b through double reduction gearing contained in gear reduction casings 15 and 16.

There is preferably a screw down motor and double reduction gearing for each roll adjusting screw 14, and the reduction gearing jack shafts 18a and 18b of the screw down motors 17a and 17b, respectively, are preferably adapted for being connected together in the usual manner by a magnetic clutch 19.

For the purposes of description, the speed reduction between each screw down motor 17a or 17b and its corresponding roll adjusting screw 14 may be considered to be 1000:1; and one revolution of the roll adjusting screw 14 may advance the screw one inch. Of course, it is understood that other screw down motor gear reduction ratios and other roll adjusting screw leads may be utilized, the above relations being taken as usual ones, merely for convenience in describing the present invention.

The work rolls 7 and 8 are driven in the usual manner through couplings 20 connected with the usual pinions in the pinion case 21, by the main mill drive motor 22 through the usual gear reduction unit 23.

In the above detailed description, a usual arrangement of a roll stand and driving and screw down means therefor has been described, the same being shown as a four high roll stand and may be the last stand of a tandem arranged continuous either hot or cold rolling mill through which the material M being rolled passes from the entering side indicated at A in Fig. 2 between the work rolls 7 and 8 where reduction takes place, and out of the mill stand at the delivery side B traveling in the direction of the arrow shown in Fig. 2, all of which is standard practice.

While our invention is described in connection with the particular type of mill shown, it will be understood by anyone skilled in the art that the invention may be carried out in connection with other usual types of mills.

Proceeding now to the detailed description of the interconnected mechanical and electrical devices utilized for rolling uniform gauge material, a cam 24 is preferably mounted on the screw

down motor jack shaft 18a, preferably a hydraulic variable speed transmission indicated generally at 25 is connected preferably by a coupling 25a to the drive shaft of the main mill motor 22, and a cam 26 is preferably mounted on the drive shaft 27 of the screw down motor 17a.

The hydraulic variable speed transmission generally indicated at 25 may preferably include what is generally termed a hydraulic pump 28, which is directly connected to and operates at the speed of the main mill drive motor 22, and also includes a hydraulic motor 29 driven by pump 28 through a hydraulic connection 30. The speed of the shaft 31 of the hydraulic motor 29 is variable and may be controlled by the hydraulic variable speed transmission controller 32. A cam 33 is mounted on the shaft 31 of the hydraulic pump 29.

Referring to the wiring diagram shown in Fig. 3, the mill drive motor is diagrammatically indicated at 22, the mill screw down motors are diagrammatically indicated at 17a and 17b and the shafts 18a, 27 and 31, together with their respective cams 24, 26 and 33 are diagrammatically shown.

For convenience in description, the various circuits shown in the wiring diagram of Fig. 3 may be generally referred to as the mill drive motor circuit, the screw down actuating circuit (down), the screw down holding circuit (down), the screw down contactor circuit (down), the screw down actuating circuit (up), the screw down contactor circuit (up) and the screw down motor circuits down and up.

The mill drive motor circuit includes wires 34 and 35 leading from line wires 55 and 56 to the usual drive motor control switches 36, wire 37 leading from the control switches 36 to the mill drive motor 22, wire 38 leading from the mill drive motor to the double acting relay coil 39 in series with the mill drive motor 22, and wire 40 leading from the coil 39 to the drive motor control switches 36.

The screw down actuating circuit (down) includes wire 41, leading from line wire 56 to the armature 42 of the double acting series relay controlled by the coil 39, the armature 42 being preferably pivoted at 43, contact 44 on armature 42, contact 45, wire 46, contact 47, switch blade 48, contact 49, wire 50, wire 51, shunt relay coil 52, wire 53, and wire 54 leading to line wire 55.

The switch blade 48 of the screw down actuating contact making switch, is preferably provided on a lever 57, pivoted at 58, and carrying a roller 59, which rides on the cam 33 mounted on the shaft 31 of the hydraulic pump 29. When the roller 59 rides in the recess 33a of the cam 33, as shown in Fig. 3, switch blade 48 closes the circuit between the contact points 47 and 49; and when the roller 59 rides on the outer periphery 33b of the cam 33, switch blade 48 opens the circuit between contact points 47 and 49.

The screw down holding circuit (down) includes wire 60 leading from line wire 56 to contact 61, switch blade 62, contact 63, wire 64, contact 65, switch blade 66, contact 67, wire 68, wire 51, shunt relay coil 52, wire 53, and wire 54 leading to line wire 55.

The switch blade 62 of the screw down limit switch (down), is preferably provided on a lever 69, pivoted at 70, and carrying a roller 71, which rides on the cam 26 mounted on the shaft 27 of the screw down motor 17a. When the roller 71 rides on the periphery 26a of the cam 26, as shown in Fig. 3, the switch blade 62 closes the circuit between the contact points 61 and 63;

and when the roller 71 rides on the projection 26b of the cam 26, switch blade 62 opens the circuit between contact points 61 and 63.

The switch blade 66 of the shunt relay controlled by the coil 52 is preferably mounted on an insulating block 72 carried by one arm 73 of the bell crank armature 74 of the shunt relay, pivoted at 75.

The screw down contactor circuit (down) includes wire 76 leading from line wire 56, wire 77, armature 74, contact 78 carried by armature 74, contact 79, wire 80, wire 81, screw down motor shunt relay down contactor coils 82, wire 83, and wire 84 leading to line wire 55.

The screw down actuating circuit (up) includes wire 41, leading from line wire 56 to armature 42 of the double acting series relay controlled by the coil 39, contact 85 on armature 42, contact 86, wire 87, contact 88, switch blade 89, contact 90, wire 91, shunt relay coil 92, wire 93, and wire 54 leading to line wire 55.

The switch blade 89 of the screw down limit switch (up) is preferably provided on a lever 94, pivoted at 95, and carrying a roller 96, which rides on the cam 24 mounted on the jack shaft 18a of the screw down motor 17a. When the roller 96 rides on the outer periphery 24a of the cam 24, as shown in Fig. 3, the switch blade 89 closes the circuit between contact points 88 and 90; and when the roller 96 rides on the projection 24b of the cam 24, switch blade 89 opens the circuit between contact points 88 and 90.

The screw down contactor circuit (up) includes wire 76 leading from line wire 56, wire 97, armature 98 pivoted at 99 controlled by shunt relay coil 92, contact 100 carried by armature 98, contact 101, wire 102, wire 103, screw down motor shunt relay up contactor coils 104, wire 83, and wire 84 leading to line wire 55. The up and down screw down contactor circuit wires 81 and 103 may also preferably be connected to usual screw down motor control switches indicated diagrammatically at 105, which may also be connected by wire 106 to line wire 56.

The screw down motor circuit for each screw down motor 17a and 17b, when the motors are to be operated to run the screws 14 down, each includes wire 107 leading from line wire 56, wire 108, contact 109, contact 110 carried by armature 111 controlled by one of the shunt relay down contactor coils 82, wire 112, wire 113, screw down motor 17a or 17b, wire 114, wire 115, armature 116 controlled by the other shunt relay down contactor coil 82, contact 117 carried by armature 116, contact 118, wire 119, and wire 120 leading to line wire 55.

The screw down motor circuit for each screw down motor 17a and 17b, when the motors are to be operated to run the screws 14 up, each includes wire 107 leading from line wire 56, wire 121, contact 122, contact 123 carried by armature 124 controlled by one of the shunt relay up contactor coils 104, wire 125, wire 114, screw down motors 17a or 17b, wire 113, wire 126, armature 127, controlled by the other shunt relay up contactor coil 104, contact 128 carried by armature 127, contact 129, wire 130, and wire 120 leading to line wire 55.

When the mill drive motor is operating under load, when material M being rolled enters between work rolls 7 and 8, and during the entire time of passage of material M through the mill, the coil 39 is energized so as to hold the armature 42 of the double acting series relay in the position shown in Fig. 3 of the drawings, so that the con-

tact points 44 and 45 are closed and the contact points 85 and 86 are open. When the mill drive motor is operating at no load, as when the rear end of the material M being rolled is delivered 5 from the work rolls 7 and 8, the coil 39 becomes deenergized and the armature 42 moves to a position opening contacts 44 and 45 and closing contacts 85 and 86.

The contacts 44 and 45 are in the screw down 10 actuating circuit (down) and the contacts 85 and 86 are in the screw down actuating circuit (up), so that the mill drive motor circuit, or the load on the mill drive motor, or the passage of material between the work rolls 7 and 8 controls the screw 15 down actuating circuit (down) and screw down actuating circuit (up).

In order for the screw down actuating circuit (down), and therefore the shunt relay coil 52 to be initially energized, to move the armature 74 to 20 the position shown in Fig. 3, the switch blade 48 must close the circuit between contacts 47 and 49, and this condition only occurs when the roller 59 rides in the recess 33a of the cam 33, so that the screw down actuating contact making switch 25 secondarily controls the screw down actuating circuit (down).

As soon as the coil 52 has been energized by the screw down actuating circuit (down) to move the armature 74 to the position shown in Fig. 3 30 of the drawings, the switch blade 66 connects contact points 65 and 67 to close the screw down holding circuit (down), provided that the switch blade 62 connects contacts 61 and 63 by the roller 71 riding on the periphery 26a of the cam 26, to 35 maintain the coil 52 energized so as to hold the armature 74 in the position shown in Fig. 3 of the drawings after the screw down actuating circuit (down) may be deenergized when the roller 59 rides on the periphery 33b of cam 33 to open the 40 circuit between contacts 47 and 49. Since the armature 74 is in the screw down contactor circuit (down), the screw down actuating circuit (down) followed by the screw down holding circuit (down) controls the screw down contactor circuit (down).

45 As long as the armature 74 is in the position shown in Fig. 3 of the drawings, the screw down contactor circuit is energized and the screw down shunt relay down contactor coils 82 hold the down relay armatures 111 and 116 in the position shown 50 in Fig. 3 to complete the screw down motor circuits (down) so that the screw down motors 17a and 17b will run the screws 14 down.

When the switch blade 62 disconnects contact 55 points 61 and 63, by the roller 71 riding on cam 26b, the screw down holding circuit (down) is deenergized so that the coils 82 are deenergized, which results in contact being broken between contact points 109 and 110, and 117 and 118; so 60 that the screw down motor circuits (down) are deenergized and the screw down motors 17a and 17b cease to move the screws 14 down. Thus, the screw down contactor circuit (down) controls the screw down motor circuits (down).

When the mill drive motor is operating at no 65 load, the mill drive motor circuit is deenergized and the armature 42 moves to a position closing the contacts 85 and 86 in the screw down actuating circuit (up). When the switch blade 89 connects contacts 88 and 90, during the time when the roller 96 is riding on the peripheral surface 24a of the cam 24, the screw down actuating circuit (up) is energized to energize the coil 92 and draw the armature 98 to a position closing contacts 100 and 70 101 so that the screw down contactor circuit (up) 75 is energized. The screw down actuating circuit

(up) therefore controls the screw down contactor circuit (up).

When the screw down contactor circuit (up) is energized, the screw down shunt relay up contactor coils 104 hold the up relay armatures 124 and 121 in a position to close contacts 122 and 123, and 128 and 129 to complete the screw down motor circuits (up) so that the screw down motors 17a and 17b will run the screws 14 up 10 until the roller 96 rides on the cam projection 10 24b when the switch blade 89 disconnects contacts 88 and 90, deenergizing the screw down actuating circuit (up). At this time, armature 98 is released, deenergizing the screw down contactor circuit (up) and the shunt relay coils 104 15 are deenergized to break the screw down motor circuits (up).

Assume that the material M to be rolled finishes approximately three hundred feet in length, and that a gauge variation from forward to rear 20 end of such a finished piece is .010 inch. Assume, further, that the diameter of the work rolls 7 and 8 is approximately 18 inches so that the periphery of the same is approximately 5 feet. Thus, each revolution of the rolls 7 and 8 25 advances 5 feet of material through the rolls. Accordingly, 6 revolutions of the work rolls 7 and 8 advances 30 feet of material M through the rolls. With the assumed screw down motor gear reduction ratio of 1000:1 and the assumed roll 30 adjusting screw lead of 1 inch, for every revolution down of the screw down motors the roll adjusting screws 14 move down .001 inch and decrease the gap between the work rolls 7 and 8 .001 inch. 35

Therefore, if the screw down motors are caused to make one revolution, every time 30 feet of material M pass through the mill in rolling a 300 foot strip, 10 adjustments of .001 inch each are made, which decreases the gap between the work 40 rolls 7 and 8, a total of .010 inch and compensate for the .010 inch gauge variation which would otherwise occur, with the result that the delivered material has a uniform gauge from end to end. 45

In order to secure the periodic or intermittent 45 operation of the screw down motors (down) at intervals of 30 foot passage of material through work rolls 7 and 8, the screw down actuating circuit (down) must be energized once every 6 revolutions of the work rolls 7 and 8, and this is 50 accomplished by adjusting the hydraulic speed transmission controller 32 so that the cam 33 makes one revolution for every 6 revolutions of the work rolls 7 and 8.

Of course it will be understood to those skilled 55 in the art that the hydraulic variable speed transmission 25 may be connected to the gear reduction unit 23 rather than to the main mill drive motor 22, or at any other desirable place, so that the speed of the cam 33 may be coordinated with the speed of the rolls 7 and 8 and therefore with the passage of the material through the mill. 60

When the nature of the material being rolled requires greater or less corrections to be made to 65 compensate for gauge variation, the same may be accomplished by changing the ratio of the speed of the cam 33 to that of the work rolls 7 and 8 and therefore to the passage of material through the mill. It is for this purpose that a hydraulic 70 variable speed transmission is preferably utilized so that variable speeds for the cam 33 may be readily obtained when desired; but it will be readily understood by those skilled in the art 75 that other means may be provided for obtaining

variable speed adjustments for the cam 33 coordinated with the rotation of the work rolls 7 and 8.

One revolution of the screw down motor 17a, keeping the above assumptions in mind, makes a .001 inch adjustment of the roll adjusting screw 14, and the cam 26 in being directly connected to the shaft 27 of the screw down motor 17a causes the screw down holding circuit (down) to be deenergized with each revolution of the screw down motor 17a, so as to stop the screw down motor. If it is desired to change the amount of the intermittent adjustment of the gap between the work rolls 7 and 8, to something other than .001 inch per adjustment, the ratio of revolutions of the cam 26 with respect to the screw down motor 17a may be changed in any suitable manner.

In the case assumed above, ten down adjustments of the screw 14 are performed by the screw down motor 17; and ten revolutions of the screw down motor and of the cam 26 occur in performing the adjustments. Meanwhile, the screw down jack shaft 18a does not make a complete revolution, so that the roller 96 rides on the periphery 24a of the cam 24 during the entire time of intermittent down movement of the screws 14.

In Fig. 3, the cam 26 is indicated by an arrow as rotating in a clockwise direction during down rotation of the screw down motors, while the cam 24 rotates, as shown by the arrow, in a counter-clockwise direction during down movement of the screw down motors. When the screw down motors are running up, the cam 24 rotates in a clockwise direction, as shown by the arrow, until the cam projection 24b operates lever 94 to disconnect contacts 88 and 89, when the roll gap adjustment has been returned to its original setting upon delivery of the rear end of the material from the rolls, to deenergize the screw down actuating circuit (up), and therefore the screw down contactor circuit (up), and finally the screw down motor circuits (up).

The operation of our improved method and apparatus for rolling uniform gauge strips and the like may be briefly summarized as follows:—

The mill starts with no load on it and the screws 14 are set in an "up" positioned for rolling a selected gauge. The front end of material to be rolled enters between the work rolls 7 and 8 and upon engagement of the rolls with the material, sufficient current passes through the mill drive motor circuit to energize the coil 39 to draw the armature 42 to the position shown in Fig. 3 of the drawings.

After the rolls 7 and 8 have made not over six revolutions, the cam 33 causes the switch blade 48 to make contact between contact points 47 and 49, thus energizing the screw down actuating circuit (down), which in turn energizes the screw down contactor circuit (down) to close the screw down motor circuits (down), and the screw down motors start running the screws 14 down.

Meanwhile, upon rotation of the screw down motor 17a, the cam 26 operates the screw down limit switch (down) to make contact between contact points 61 and 63 to energize the screw down holding circuit (down) and maintain the coil 52 energized after the screw down actuating circuit (down) has been deenergized by continued rotation of the shaft 31 to operate the screw down actuating contact making switch to disconnect contact points 47 and 49.

The distance that the screws travel down is limited by operation of the cam 26, and the screws 14 come to rest when the cam 26 makes one revolution, during which time the screws have travelled down a predetermined amount.

When the material has moved forward through the rolls 7 and 8 approximately 30 feet, the cam 33 again causes contact to be made between contact points 47 and 49 and the above operations are repeated. The intermittent operation of the screw down motors is continued at the stated predetermined intervals as long as material is passing through the mill and a load remains on the mill drive motor 22, so that the screw down motors operate in synchronism with the rotation of the work rolls to adjust the gap between the work rolls during passage of material through the rolls.

When the rear end of the material is delivered from the mill, the load on the driving motor is removed and the coil 39 is deenergized, releasing the armature 42 and energizing the screw down actuating circuit (up). Thereupon, the screw down contactor circuit (up) and consequently the screw down motor circuits (up) are energized and the screw down motors return the screws 14 to their original "up" position, when the cam 24b operates the screw down limit switch (up) to open the screw down actuating circuit (up); and the mill is ready for rolling another piece.

There are only two variables which exist and these are the variable lengths of material to be rolled and the different gauge variations existing from end to end of pieces. When the improved method and apparatus for rolling uniform gauge strips and the like is originally installed, it will probably be necessary to roll one or two pieces and determine the value of the gauge variation, whereupon the various adjustments may be made to accomplish gauge compensation.

In certain cases, it may be convenient or necessary to compensate for gauge variations, in continuously rolling material on a continuous rolling mill, at a roll stand other than the last finishing stand of a continuous train, or at a plurality of roll stands of the continuous train. It is therefore comprehended within the scope of the present invention to compensate for gauge variation of material being rolled in a continuous rolling mill at one or more of any of the stands of a continuous train of tandem arranged mills.

The present improvements accordingly provide for the hot or cold rolling of uniform gauge material such as strips, sheets, stripsheets and the like, in a rolling mill regardless of the length of material rolled or of the value of the gauge variation from end to end of the material, which is to be compensated for. Moreover, the present improvements may be readily applied to existing rolling mill equipment for correcting the gauge variation difficulties experienced in continuous rolling.

We claim:—

1. In a rolling mill including work rolls and screw down means, means for operating the screw down means intermittently to adjust the gap between the rolls a predetermined amount during movement of material through the rolls, and means operated by the entry of material between the rolls for actuating the said operating means.

2. In a rolling mill including work rolls set to roll a selected gauge material and screw down means, means for operating the screw down

- means intermittently to adjust the gap between the rolls a predetermined amount during movement of material through the rolls, means operated by the entry of material between the rolls 5 for actuating the said operating means, and means operated upon delivery of material from the rolls to return the screw down means to the original roll gap setting.
3. In a rolling mill including work rolls and screw down means for the work rolls, means for operating the screw down means a predetermined amount at predetermined intervals during movement of material through the rolls, and means for varying the said intervals.
- 10 4. In a rolling mill including work rolls and screw down means for the work rolls, means for operating the screw down means at equal time intervals for equal time periods to progressively adjust the gap between the rolls during movement of material through the rolls.
- 15 5. In a rolling mill including work rolls and screw down means for the work rolls, means periodically operating the screw down means every time the rolls make a predetermined number 20 of revolutions to adjust the gap between the rolls during movement of material through the rolls.
- 25 6. In a strip rolling mill including work rolls and screw down means for the work rolls, means periodically operating the screw down means to cumulatively adjust the gap between the rolls every time a predetermined length of strip and successive equal lengths of strip pass through the rolls from the entry of the strip between the rolls until delivery of the strip from the rolls.
- 30 7. In a strip rolling mill including work rolls and screw down means for the work rolls, means periodically operating the screw down means to cumulatively adjust the gap between the rolls 35 an equal amount every time each of successive equal fractional lengths of strip pass through the rolls from the entry of a strip between the rolls until delivery of the strip from the rolls.
- 40 8. In a rolling mill for rolling uniform gauge material from material having a varying gauge progressively heavier from front to rear end, work rolls, screw down means for the work rolls, and means automatically operating upon the entry of material between the rolls until delivery 45 of the material from the rolls for actuating the screw down means at intervals to progressively decrease the gap between the rolls.
- 50 9. In a rolling mill including work rolls, a mill drive motor for the work rolls, screw down means, driving means for the screw down means, means for periodically operating the driving means at intervals to periodically adjust the gap between the rolls, and means automatically actuating said operating means when the mill drive 55 motor is running under load.
- 55 10. In a rolling mill for maintaining the gauge of the material rolled substantially constant, work 60 rolls, screw down means for the work rolls, and means periodically operating the screw down means a predetermined amount to cumulatively adjust the gap between the work rolls during movement of the material through the rolls.
- 5 11. In a rolling mill for substantially eliminating gauge variations in the material rolled resulting from the gradual cooling of the material while being rolled, work rolls, a mill drive motor for the work rolls, screw down means for the work rolls, and means actuated by the mill drive motor for operating the screw down means periodically a predetermined amount to cumulatively adjust the gap between the work rolls during movement of the material through the work rolls.
- 10 12. The method of rolling metal in a rolling mill to maintain the gauge of the rolled metal substantially constant, which includes periodically and cumulatively adjusting the gap between the mill rolls every time the rolls make a predetermined number of revolutions automatically when metal is moving forward through the rolls.
- 15 13. The method of rolling metal in a rolling mill to maintain the gauge of the rolled metal substantially constant, which includes progressively decreasing the gap between the mill rolls at equal time intervals for equal time periods automatically when metal is moving forward through the rolls.
- 20 14. The method of rolling a uniform gauge strip in a rolling mill from a strip having a varying gauge progressively heavier from front to rear end, which includes automatically adjusting the gap between the mill rolls a predetermined amount every time each of successive fractional lengths of strip pass through the rolls from the entry of the strip to the rolls to the delivery of the strip from the rolls, and controlling the actuation of the automatic adjustment by the load on the mill drive motor.
- 25 15. The method of rolling metal in a rolling mill to maintain the gauge of the rolled metal substantially constant, which includes progressively adjusting the gap between the mill rolls at equal time intervals for equal time periods automatically when metal is moving forward through the rolls, and automatically returning the roll gap adjustment to the original setting upon delivery of the metal from the rolls.
- 30 16. The method of rolling metal in a rolling mill to maintain the gauge of the rolled metal substantially constant, which includes periodically adjusting the gap between the mill rolls at equal time intervals for equal time periods automatically when metal is moving forward through the rolls, automatically returning the roll gap adjustment to the original setting upon delivery of the metal from the rolls, and controlling the actuation of said automatic adjustments by the load on the mill drive motor.
